ILLUMINATING FLARE

Ralph H. Halbach, Oakland, Calif.

Application July 7, 1936, Serial No. 89,281

4 Claims. (Cl. 102—24)

The invention relates to illuminating flares and more particularly to aerial flares which are adapted to be released from air-craft and the like at relatively high altitudes, in periods of darkness and, which, during their gravitation, illuminate the surrounding area.

An object of the invention is to provide an aerial flare of the character described which may be dropped from substantially any altitude desired and will, at an adjustably predetermined height, cause the release of the parachute or other gravitational retarding means and the ignition of the flare so as to produce a slow descent of the device while illuminating the surrounding terrain for a considerable distance.

Another object of the invention is to provide a device of the character above, which will embody an improved construction of a flare providing for a reduction of destructive interference of light in the flare itself with a corresponding increase in the light radiation of the flare.

A further object of the invention is to provide a device of the above character having an improved means for igniting a flare or other aerial device during gravitation.

The invention possesses other objects and features of advantage, some of which, with the foregoing, will be set forth in the following description of the preferred form of the invention which is illustrated in the drawings accompanying and forming a part of the specification. It is to be understood, however, that variations in the showing made by the said drawings and description may be adopted within the scope of the invention as set forth in the claims.

Referring to said drawings:

Figure 1 is a vertical sectional view of an illuminating flare constructed in accordance with the present invention.

Figure 2 is a transverse sectional view of the flare proper.

Figure 3 is a transverse sectional view showing the timing mechanism of the device.

Figure 4 is a longitudinal sectional view of the timing mechanism.

Figure 5 is a fragmentary side elevation of a portion of the device.

Figure 6 is an end view of the collapsible parachute container.

Figure 7 is a side elevation of the container.

Figures 8 and 9 are fragmentary side elevations of the container.

Figure 10 is a side elevation of the sectional parachute container shown with the sections partly detached.

Figure 11 is an end view of the flare discharge tube.

The aerial illuminating flare illustrated in the accompanying drawings is composed of a flare proper 16 which has associated therewith a timing mechanism 17 and a parachute 18 or other gravitational retarding means, and ignition means 19. As here illustrated the timing mechanism is incorporated within a casing 21 which carries, at its upper end a collapsible casing 22 10 enclosing the parachute 18 and to the lower end of which is secured the flare 16. As will be seen from Figure 1 this assembly may be inserted into a discharge tube 23 carried by an air-craft, or the like, for releasing the device from the air- 15 craft.

The flare 16, as will be seen from Figures 1 and 2, is composed of inner and outer shells 24 and 26 which, in accordance with the present arrangement, are of cylindrical shape and concentrically arranged to define between the cylinders an axially extending annular space 27 within which is packed a suitable flare compound 28, such as a magnesium compound or the like. The shells may be formed of a slow burning material, 25 such as card-board, or the like, and are secured at their inner ends to the lower end of the casing 21 and are arranged for the ignition of the flare compound at the outer end of the annular space 27. As will be noted the inner shell or 30 casing 24 is left substantially entirely open to the atmosphere so as to supply an abundance of air to the inner circumference of the annular burning ring provided by the composition. In this manner not only is a complete combustion 35 of the flare composition insured, but the burning zone of the flare is confined to a relatively narrow circular ring. This last feature is of particular importance since, as will be understood, the thinness of the flame materially reduces the 40 destructive interference of the light produced and provides a corresponding increase in light radiation.

In accordance with the present invention the flare is normally not ignited immediately on being 45 dropped into space, nor is the parachute immediately released, but the device is allowed to fall to a predetermined distance above the ground before the parachute is released and coincident therewith the flare ignited. This substantially 50 simultaneous release of the parachute and ignition of the flare is provided for by using the force exerted by the parachute on the device when the parachute is suddenly opened to actuate the ignition means 19 of the flare. As will be seen from 55

Figure 1, this ignition means comprises a percussion squib 29 which is connected by means of a fuse 31 to a priming charge 32 at the end of the flare composition 28; the squib is exploded by a 5 firing pin 33 mounted over the squib and actuated by a trip-hammer 34, the latter being set into motion by a trigger 36 connected with the parachute. The trigger 36 is formed by an enlargement at the lower end of a rod 37 which extends 10 axially through the device from within the inner flare casing 24 to the parachute casing 22 and is connected at its upper end to the parachute 18, the rod being preferably resiliently mounted with the trigger 36 opposite the trip-hammer 34 by 15 means of a helical spring 38 surrounding the rod and secured to the bottom wall 39 of the casing 21. The resiliency of the trip-hammer is provided by a flat spring 41 mounted above and against the hammer on a backing plate 42 carrying the several elements of the ignition means. It will thus be understood, that with the parachute 18 suddenly released during the rapid fall of the device the reactive force set up by the parachute will be utilized to ignite the flare, and thus, the device 25 may be caused to rapidly descend from an aircraft or the like, at a relatively high elevation to a desired lower elevation and there ignited and caused to thereafter very slowly descend the remainder of the distance to the earth, while 30 illuminating the surrounding area, and in this manner the wastefulness of lighting a flare and releasing the parachute at the high altitude of an air-craft or the like is avoided. The spring 38, as aforementioned, provides a resilient support 35 for the rod 37 and a resilient connection between the parachute and the flare and the ignition means. Thus, as the parachute is suddenly opened during falling of the device, the shock or jerk on the connection means is to a large extent absorbed by the spring and additionally the member 36 is caused to reciprocate across the hammer 34 to cause a repetitive operation thereof insuring ignition of the squib 29.

As an important feature of the present invention 45 the distance to which the device is permitted to fall before the release of the parachute and ignition of the flare may be accurately adjusted over a wide range by the operator releasing the device. This is provided for by the use of a timing mechanism 47 which controls the stability of the collapsible casing 22 surrounding the parachute whereby after a predetermined time interval from the release of the device, the casing 22 will be dismembered and the parachute thrown 50 open and the flare ignited as above described.

The timing arrangement may be of more or less standard clock mechanism having a winding pinion 43, a spring gear 44, a clock spring 46, and a great wheel 47. The movement of the wheel 47 55 is controlled by an escapement mechanism 49 and balance heel 51, which are connected to the wheel by a suitable gear chain 48. A cam 52 is mounted on the hub of the wheel 47 and actuates a locking bolt 53 to produce an opening of the 60 parachute casing 22. As will perhaps, be best seen from Figures 1, 3 and 4, the locking bolt 53 comprises a yoke surrounding the axial rod 37 and the support therefor and adjacent one end 65 69 of the yoke is provided with a follower 54 which engages the periphery of the cam 52 and is urged thereagainst by means of a spring 56 surrounding the bolt end 69. The periphery of the cam 52 is formed with a notch 57 into which the follower 54 is sprung on alignment thereof with

the notch to release the opposite ends of the locking bolt from the casing 22.

The parachute casing 22, as illustrated in Figures 6 to 10 is comprised of a pair of half-sections 58 and 59, which are provided with lapping edges 61 and 62 through which are formed, at the opposite bottom sides of the casing, openings 63 and 64 for the receipt of the ends of the locking bolt 53. The upper ends 66 and 67 of the sections are provided with a releasable lap joint 68 which 10 is readily dis-assembled upon relative longitudinal movement of the sections. As will be seen, the opening 63 through the base of the sections receives the bolt end 69, while the opposite opening 64 received an enlarged portion at the other end 15 71 of the bolt and upon shifting of the bolt the end 69 is withdrawn from the opening 64 while a reduced portion 72 adjacent the end 71 is placed in registration with a slotted portion 73 leading from opening 64 to the end of the sections. 20

Means are provided for automatically placing the timing mechanism in operation upon the discharge of the device from the tube 23 and which here consists of a locking pin 74 which extends radially through the casing 21 of the timing mechanism and engaged in a recess 76 in the hub 77 of the great wheel 47 of the timing mechanism, and is provided with a spring 78 which urges the pin 74 to outward position removing the same from its locked position within 30 the recess aforesaid. In accordance with the present arrangement the length of the pin 74 is such that with same in its inner position the outer end of the pin will be substantially flush with the surface of the casing 21 and when the device is mounted within the discharge tube 23 the inner wall 79 of the tube will hold the pin in its inward locking position. However, on discharge of the device from the tube the pin 74 will be released and will move under urge of the 40 spring 78 to release the timing mechanism. Preferably a locking lever 81 is mounted on the casing above the pin 74 and is provided with a pall 82 which is engageable in a recess 83 in the pin for holding the latter in inward locking position when the device is removed from the discharge tube. Also, the positioning of this lever above the pin 74 makes possible the removal of the device from the outer end of the discharge tube without releasing the timing mechanism. 45 If desired, a safety slide 84 may be provided on the periphery of the casing for holding the lever 81 in the recess 83 of the pin for locking the lever 81 against the pin 74.

As will be understood, with the pin 74 in its inward position and the timing mechanism wound, the circumferential spacing of the plate 53 and the cam 57 will determine the distance through which the device will fall when discharged from the tube before the parachute is 55 permitted to open and the flare ignited. In accordance with the present arrangement this circumferential spacing may be adjusted in order that the distance through which the device falls may be accurately adjusted. This is provided by forming the casing 21 of upper and lower sections 86 and 87 which are rotatably related to each other and on the upper section 86 of which is carried the lower end of the parachute casing 22 and the locking bolt 53. Thus by adjusting the section 86 relative to the section 87, the follower 54 carried by the locking bolt 53 may be circumferentially displaced relative to the cam slot 57. Preferably, and as illustrated in Figure 60 5, a set of graduations 88 may be provided on 70 the section 86 relative to the section 87, the follower 54 carried by the locking bolt 53 may be circumferentially displaced relative to the cam slot 57. Preferably, and as illustrated in Figure 75

the abutting edges of the sections 86 and 87 for indicating the time or distance interval that the parachute will be released after the device has been discharged from the tube.

5 As will be seen from Figure 1, the device is rested within the discharge tube on a removable bottom 89 supported on a plurality of dogs 91. These dogs are, in turn, grooved and receive a plurality of spiral teeth 92 which on rotation of 10 the tube, as by means of a handle 93 cause the retraction of the dogs from under the bottom 89 and the release of the device through the open bottom end 94 of the tube. The tube may be loaded through the upper end thereof by opening 15 the removable covering 95 thereat.

While in the present embodiment a parachute has been specifically disclosed as a gravitational retardating means it will be understood that any 20 equivalent means, such as a balloon and means for inflating the same during gravitation may be used. Similarly while I prefer the type of ignition means disclosed, it will be clear that electrical and other mechanical means may be operated by the reactive force on the gravitational 25 retardating means for igniting the flare compound.

I claim:

1. An aerial device adapted to be dropped from a relatively high elevation, gravitational retarding means connected to said device, ignition 30 means for said device, timing means for operating said gravitational retarding means and said ignition means during the gravitation of said device, a discharge tube for said device, and means connected to said timing means and engageable 35 with said tube and automatically operative upon release of said device from said discharge tube to place said timing means in operation.

2. An aerial device adapted to be dropped from a relatively high altitude comprising, a casing, gravitational retarding means carried by said casing, a mechanism for placing into operation said means during gravitation of said device and including an operating member extending from a side of said casing, a discharge tube for said casing and engageable with said member for holding said mechanism inoperable whereby on 10 ejection of said device from said tube said member will be released to automatically place said timing mechanism in operation.

3. An aerial device adapted to be dropped from a relatively high altitude comprising, a casing, a parachute carried by said casing and releasable 15 therefrom during gravitation of said device, ignition means furnished with said casing and including a reciprocative operating member, and means separate from said ignition means and resiliently connecting said parachute with said 20 ignition means and causing an oscillation of said ignition means upon opening of said parachute.

4. An aerial device adapted to be dropped from a relatively high altitude comprising a casing, 25 a parachute normally folded in said casing, means operable to release said parachute during gravitation of the device, a second casing and ignition means carried by said second casing, and resilient means separate from said ignition 30 means connecting said parachute and second casing and operable upon opening of said parachute to operate said ignition means and to absorb a substantial part of the shock caused by the sudden check of the gravitation of the device 35 on opening of said parachute.

RALPH H. HALBACH.
